UNITED STATES PATENT OFFICE

2,599,772

WAGON HOIST

Donald E. Moore, Kokomo, and Herman Doyle
Moore, Frankfort, Ind.

Application February 10, 1949, Serial No. 75,612

1 Claim. (Cl. 254—144)

1
This invention relates to a wagon hoist and the like.

The chief object of this invention is to provide a portable hoist structure through which a loaded vehicle may be drawn and when disposed over the same and the tractive force such as a tractor or a team is disconnected, the latter may be connected to a windlass or drum mounted cable so that continuation of the movement of said tractor or team in the preceding direction will result in the elevation or hoisting of that portion of the vehicle disposed immediately above the central portion of the lifting device.

Said device is further characterized by the fact that backing up of the team or tractor, when so cable connected, automatically results in the return or lowering of the elevated vehicle or portion thereof. When full return is accomplished, the tractive force may be reconnected to the vehicle and tractive force applied in the same general direction as before whereupon the vehicle is passed through the hoist structure.

The chief feature of the invention resides in an open work base from which there projects upwardly two end frames spaced apart a sufficient distance to accommodate vehicles as wide as hay wagons, etc. Also associated with said base is an elevating structure, the same being pulley and cable or rope elevated in conjunction with a drum having spaced cable or rope winding portions and an intermediate tractive cable, chain or like winding portion. The latter being rotatable by straight-away movement of the last mentioned cable, in opposite directions for load raising and load lowering, respectively.

Another feature of the invention resides in one of the end frames being of singular character and biased braced, and the other end frame being of dual character and cross or like braced, the latter rotatively supporting the winding drums.

Another feature of the invention resides in the sled-like formation of the base to facilitate portability.

A further feature of the invention resides in the guide and cushion stop structure for the drive away cable connector or hitch.

A still further feature of the invention resides in a semi-yielding safety connection between the hoisting cables and the elevator portion of the device.

The full nature of the invention will be understood from the accompanying drawing and the following description and claims.

In the drawings,

Fig. 1 is a front view of the hoist structure embodying the invention.

2

Fig. 2 is a top plan view thereof.

Fig. 3 is an end elevational view at the drum or windlass end.

In the drawings 10 indicates a pair of parallel runners having upturned ends 10a and suitably spaced apart. At one end is a single side frame structure 11 and at the other end is a double or dual end frame structure 12 and 13, suitably connected together by cross-braces 14 and 15. Said 10 double end frame is also connected together and braced by angle iron supports 24 and 25.

The singular frame 11 is braced by the biased braces 11a. Each of the aforesaid frames, at the top, mounts a pulley as for example, pulleys 16, 17 and 18 respectively. Approximately directly therebeneath and near the base are the pulleys 19 and 20.

The elevator or platform comprises a pair of members 21 disposed within the open type base 20 and parallel to the members 10 thereof. Said elevator members are connected at the ends by the angle iron members 22 and may be centrally connected by a central bearing plate 23. Said angle iron members 22 carry the guide bars 26.

An elevating shaft 27 is bearing mounted as at 29 between said double end frames and secured to a support angle iron member 25. Said shaft has at each end thereof an elevating drum as at 31 and 32, see Fig. 1. A windlass or winding drum 33 is rigidly mounted on said shaft between the elevating drums 31 and 32.

The winding drum 33 has a cable or rope 34 secured thereto and wound thereon. Said cable passes from the drum through a guide pulley and bracket 35, see Fig. 2, and also through a cushion stop structure 36 and into a stop member 37 and terminates in a hitch connector 38. Said connector is a loop made by doubling back the end of said cable and which is secured by clamp 39.

A cable or rope 40 is secured to elevating drum 31 and passed upwardly, and between the pulley guide 41 and pulley 17, then downwardly to and through the pulley housing 42 which supports the elevating pulley 43. The cable 40 is then passed upwardly and secured to the deadman 44 as at 45, see Fig. 3.

A cable 46, see Fig. 1, is secured to elevating drum 32 and passed upwardly and between the pulley guide 47 and pulley 18 and thence downwardly to and through the pulley guide 48 and pulley 20. The cable 46 then passes below the wagon elevating platform and through the pulley guide 49 and pulley 19. It then passes upwardly through pulley guide 50, over pulley 16 and down to and through the pulley housing 51 which sup-

3

ports pulley 52. Said cable is then passed upwardly and secured to the deadman 53 as at 54.

Pulley housing 42 or 51, respectively is connected to a sling 55, see Fig. 3. Said sling comprises a cable or rope which passes from the housing aforesaid to and about the elevator members 21. It is secured to the housing as at 57 by suitable clamping means.

Paralleling said sling is a cushion connection comprising an eye-bolt 59 suitably secured to angle iron member 22 on the platform, and connected to one end of a very stiff spring 60 which in turn is connected to eye-bolt 56 secured in turn to the clamping means shown at 57. Initial platform elevation extends these springs.

The invention operates in the following manner: The tractive force passes through the hoist structure and positions the wagon or object to be lifted above the central bearing plate 23. Said tractive force is then disconnected and connected to the traction cable 34. The tractive force then moves away from the hoist structure in a substantially forward direction, thereby withdrawing the traction cable from its drum which in turn rotates the shaft and thereby winds up the two elevating cables 40 and 46 that are secured to the drums 31 and 32 which are rigid with said shaft. The two elevating cables when wound upon said drums will effect the raising of the elevating platform structure, thereby elevating said wagon. Movement of the tractive force in the opposite direction permits reverse operation of the aforesaid and effects lowering of the wagon or load and platform structure. The cushion stop then functions as previously described.

While the invention has been illustrated and described in great detail in the drawings and foregoing description, the same is to be considered as illustrative and not restrictive in character.

4

The several modifications described herein as well as others which will readily suggest themselves to persons skilled in this art, all are considered to be within the broad scope of the invention, reference being had to the appended claim.

The invention claimed is:

A wagon elevating mechanism comprising in combination, a supporting base, a pair of triangular end frames extending upwardly from said base with the apex of the triangle at the top, a platform structure disposed between said end frames, guide means on the opposite ends of said platform structure embracing the legs of said end frames, cable pulleys at the apexes of said triangular frames, cables passing over said pulleys, flexible means connecting the operating ends of the cables with the platform and biasing means shorter than said first mentioned means connecting the operating ends of the cables with the platform.
